UNITED STATES PATENT OFFICE.

JOHN M. FORBES, OF MILTON, MASSACHUSETTS, ASSIGNOR TO THE CHICAGO,
BURLINGTON AND QUINCY RAILROAD COMPANY.

SLEEPING-CAR.

SPECIFICATION forming part of Letters Patent No. 250,224, dated November 29, 1881.

Application filed August 12, 1881. (No model.)

To all whom it may concern:

Be it known that I, JOHN M. FORBES, of 5
Milton, in the county of Norfolk, State of Mas-
sachusetts, have invented certain new and use-
ful Improvements in Sleeping-Cars, of which
the following is a specification, reference being
had to the accompanying drawings.

In the ordinary sleeping-car now in use in the
United States there is provided an aisle through
10 the center of the car, and a series of sections
with upper and lower berths of equal width on
each side of the central aisle. In addition to
these sleeping accommodations there is some-
times a state-room at the end of the car, with a
15 narrow passage between it and one side of the
car, communicating with the central aisle.
There are serious objections against this plan
of constructing a sleeping-car:

First. Travelers object to being shut up in the
20 ordinary state-rooms as now constructed, be-
cause they are close, poorly lighted and venti-
lated, and afford no view of the rest of the car.
Besides this, on account of the very narrow
25 aisle at one side of the car, it is inconvenient
to enter or go out of the car.

Second. The unavoidable exposure incident
to the use of ordinary sections, and the impos-
sibility of entire seclusion while occupying them
either for sleeping or as seats during the day-
30 time, is a source of much dissatisfaction.

It is the object of my invention to overcome
these objections, and to provide a car with one
or more state-rooms which will afford complete
seclusion whenever it is desired, and which will
35 also afford a view of the entire car and the ad-
vantages of light and ventilation of the whole
car at the pleasure of the occupant. Accord-
ingly, I provide a state-room at one end of a
40 sleeping-car, as usual, but of a width less than
that of the ordinary state-room, and a set of
single seats or a half-section on the opposite
side of the car, with an aisle between, a little
45 to one side of the center of the car. Instead of
making solid partitions for my state-room, as
is usual, I make partitions with their upper
parts of open wire or wicker work, or the like,
and in connection with these open partitions I
employ the ordinary leather or other suitable
curtains, which may be drawn over them at

will whenever the occupants of the state-room 50
desire seclusion. My improved construction
admits of the introduction of my state-room at
one or both ends of the car, or of filling the en-
tire car-body with state-rooms and dispensing
with the ordinary sections on opposite sides of 55
the car. Thus my invention comprehends at
once the advantages of the entire seclusion of
passengers from each other, when desirable, ac-
cording to the English system, and the advan-
tages of free communication, according to the 60
less exclusive social habits of Americans.

In the accompanying drawings, illustrating
my invention, Figure 1 is a plan view of a por-
tion of a sleeping-car embodying my improve-
ments. Fig. 2 is a longitudinal vertical section 65
of the same, through the line 22 of Fig. 1, and
Fig. 3 is a transverse section through the line
33 of Fig. 1.

A indicates a car-body, and B my state-room
upon one side, occupying one-half or a trifle 70
more of the width of the car.

C indicates an aisle of ordinary width a lit-
tle to one side of the center of the car, and D
a half-section upon the opposite side of the car,
with single-seat accommodations.

E indicates the state-room door, opening from
the aisle within the room, which may be pro-
vided with a mirror on the inside.

F F indicate the double seats in the state-
room for use in the day-time, and the state-room 80
should be provided with the usual upper and
lower berths of an ordinary section. The space
G between the inner ends of the seats and the
aisle-partition H affords sufficient room for
dressing and undressing, and may be occupied 85
at one end by a cushioned drop-seat, I, that,
when not needed for use, may be turned up or
down against the partition to give room. The
opposite end of this space G may be occupied
by a similar seat, or by a small wash-stand and 90
its appliances, or by a combined lavatory and
water-closet, such as described in United States
Patent No. 248,914, so that when the lavatory
is raised up out of the way, as set forth in the
patent, the cushioned cover over the water- 95
closet affords another seat for the state-room.
Thus my state-room can be provided with all
the appliances and conveniences of a sleeping-

room at a hotel, including two seats, a mirror, wash-stand, water-closet, and room enough to wash and dress with convenience, so that it is possible to perform a complete toilet without 5 emerging from the state-room, and an invalid or any other traveler may conveniently remain in the state-room with every comfort from the beginning to the end of a long journey, at the same time having the benefit of light, ventilation, and a view of the entire car, and communication with his fellow passengers at his pleasure.

The aisle-partition H and the end partitions, K, of the state-room are made solid from the floor to the height of the tops of the seat-backs, 10 and from thence upward they are made of light open wire or wicker work L or the like, and are provided with suitable curtains, M, controllable from within.

In addition to the foregoing I have devised 15 another improvement in the construction of sleeping-cars, which is designed to be applied in one end of a car for the special accommodation of invalids and their attendants, or ladies traveling with nurses and small children, or 20 other travelers desiring greater accommodations than a single state-room affords. This improvement consists in what may be termed an apartment or suite of apartments with communicating rooms. It involves the same con- 25

veniences as to open-work partitions, the location of the aisle, doors, &c., as above described. Referring to the drawings with reference to 30 this improvement, N indicates what I term, in order to better distinguish it, a "parlor state- 35 room," and O another state-room, the two communicating by means of a door, P. The end partition, Q, and the aisle-partition R of the parlor state-room are to be formed in their upper parts of open-work, as above described, 40 while the partitions of the communicating state-room O are preferably made solid. Each state-room is to be provided with a door open-

ing from the aisle inward, as shown, and seats should be provided at S and T, with one of which may be combined a water-closet and 45 lavatory, as above set forth.

The parlor state-room N, I propose to provide with a sofa, U, which may be converted into a bed at night. Such a construction and combination of conveniences will accommodate a 50 special class of travelers with their attendants, and render it nearly as safe and convenient for them to be transported great distances as to remain at home or at a hotel, while not interfering with convenient passing in and out 55 through the car.

Having thus described my improvements, what I claim as new and of my own invention is—

1. In a sleeping-car, a state-room built as a 60 permanent and fixed part of the car, provided with open-work partitions on three sides within the body of the car, with or without curtains, substantially as and for the purposes set forth. 65

2. In a sleeping-car, the combination of a state-room upon one side of the car, a main aisle a little to one side of the center of the car, and a half-section on the opposite side of the car, substantially as and for the purposes set 70 forth. 75

3. In a sleeping-car, the combination of two communicating state-rooms provided with combined wood and open-work partitions, and with doors entering from the main aisle, substantially as and for the purposes set forth.

In testimony whereof I have hereunto subscribed my name this 22d day of July, A. D. 1881.

J. M. FORBES.
